UNITED STATES PATENT OFFICE.

WILLIAM FITZPATRICK, OF GIRARD, KANSAS.

WASHING-MACHINE.

SPECIFICATION forming part of Letters Patent No. 357,076, dated February 1, 1887.

Application filed July 1, 1886. Serial No. 206,833. (No model.)

To all whom it may concern:

Be it known that I, WILLIAM FITZPATRICK, a citizen of the United States, residing at Girard, in the county of Crawford and State of Kansas, have invented a new and useful Improvement in Washing-Machines, of which the following is a specification.

My invention relates to an improvement in washing-machines; and it consists in the peculiar construction and combination of devices, that will be more fully set forth hereinafter, and particularly pointed out in the claims.

In the drawings, Figure 1 is a side elevation of my invention. Fig. 2 is a vertical longitudinal sectional view of the same. Fig. 3 is a vertical transverse sectional view on line $\alpha\alpha$ of Fig. 2.

A represents a rectangular suds-box, which is provided at one end, at its lower side, with a discharge-opening, B, having a plug, C. Suitable depending legs, D, support the suds-box above the ground. In the bottom of the suds-box, at one end of the same, is located a board, D', which is supported upon a number of coiled springs, E.

F represents a frame or case comprising the vertical sides f and the transverse connecting-bars f' . In the centers of the said sides are openings f^2 , which are open on one side, as at f^3 .

G represents a series of transverse rollers, which are journaled in the sides F concentrically with the openings f^2 and extend about one-fourth around the said openings. This frame or case F rests upon the spring-board D'.

H represents a corrugated roller, which is journaled in the sides of the suds-box and is arranged concentrically with the rollers G. To one end of the shaft of the roller H is attached a gear-wheel, I, which is on the outer side of the suds box.

K represents a vertical board, which is placed in one end of the suds-box and bears against the case or frame F, the said board having on its outer side the series of coiled bearing-springs L, which bear against the opposing end wall of the suds-box.

M represents a case or frame comprising the bottom board, m , and the vertical side walls, m' . One of the said side walls has an opening, m^2 , and the other side wall has an open slot, m^3 , the

inner end of which is in a line with the opening m^2 .

N represents a small roller, having one end of its spindle journaled in the opening m^3 and the other end of its spindle bearing in the inner end of the opening m^2 . An endless apron, O, passes around the outer sides of the series of rollers G, extends longitudinally through the suds-box, and passes around the outer side of the roller N, thus connecting the said rollers N and G together. The said apron also passes under the large roller H.

P represents a roller, which is journaled in blocks R, that are attached to the upper edges of the sides of the suds-box, the said roller P being arranged parallel with the large roller H. An endless apron, S, connects the rollers H and P.

T represents a bracket, which is secured on one side of the suds-box. In the upper end of this bracket is journaled a shaft, U, to which is rigidly attached a gear-wheel, V, which meshes with the wheel I. A crank, W, is also attached to the shaft U.

The operation of my invention is as follows: When the shaft U is rotated by means of the crank W, the wheel V is turned, and imparts motion through the gear-wheel I to the large roller H, which causes the endless aprons O and S to move in the direction indicated by the arrows in Fig. 2. As the upper side of the apron O passes under the roller H, and as the apron S also passes around the said roller, it will be seen that the said aprons are in contact with each other at one end of the suds-box. A suitable quantity of suds is placed in the suds-box, and the articles to be washed are placed upon the apron O. As the said apron moves, it carries the articles between the rollers H and G, thereby subjecting them to pressure between the said rollers, and the action of the rollers on the articles forces the water or suds through and through them, thus loosening and dislodging the dirt. As the articles escape from between the rollers H and G they are carried by the apron S in the reverse direction and again dropped upon the apron O, and this operation is repeated as long as may be necessary. The suds are then drawn from the suds-box and clean water is substituted.

therefor. The operation before described is repeated, thereby thoroughly rinsing the clothes. In order to wring the clothes preparatory to hanging them upon the line, the clear water 5 is drawn from the suds-box and a spring-board having springs of greater strength is substituted for the spring-board K, thereby causing the rollers G to bear more firmly against the roller H. As the clothes are then passed successively between the rollers G and H, the water is pressed therefrom, and the clothes may be then hung upon the line.

It will be observed from the foregoing that the operation of washing the clothes may be 15 performed without handling them at all, it being only necessary to feed the clothing in the first place upon the apron O.

Having thus described my invention, I claim—

20 1. The combination of the suds-box, the roller N in one end thereof, the roller H near the opposite end of the suds-box, the rollers G, arranged around the roller H, and springs for forcing the said rollers G and H into contact 25 with each other, the roller P, the apron O, connecting the rollers N and G and passing under the roller H, and the apron S, connecting

the rollers H and P, the said apron S being in contact at one end with the apron O, and means for rotating the roller H, substantially 30 as described.

2. The combination of the suds-box, the frame M in one end thereof, and having the roller N, the frame F in the opposite end of the suds-box, and having the series of rollers 35 G, the spring-boards bearing against the under side and outer end of the frame F, the roller H, arranged concentrically with the rollers G, the said latter rollers being pressed against the said roller H by means of the 40 spring-boards, the roller P, journaled parallel with the roller H and connected thereto by the endless apron S, the endless apron O, connecting the series of rollers G and the roller M, and passing under the roller H, and means, 45 substantially as described, for rotating the roller H, substantially as described.

In testimony that I claim the foregoing as my own I have hereto affixed my signature in presence of two witnesses.

WILLIAM FITZPATRICK.
